(57) **CLAIM**

I claim the ornamental design for a dual-sided jack-o'-lantern cookie cutter, as shown and described.

DESCRIPTION

FIG. 1 is a perspective view of my new design, with the view showing principally front, left side and bottom end exterior surfaces thereof;

FIG. 2 is a front elevational view thereof;

FIG. 3 is a top end view thereof;

FIG. 4 is a bottom end view thereof;

FIG. 5 is a rear elevational view thereof;

FIG. 6 is a left side view thereof, the right side view being a mirror image hereof; and,

FIG. 7 is a perspective view showing principally rear surface portions as well as right side and bottom end exterior surfaces, together with left side and top end interior surfaces.
